UNITED STATES PATENT OFFICE.

NESTOR KALLIOINEN, OF NEGAUNEE, MICHIGAN.

RAILWAY-TIE.

1,088,586.

Specification of Letters Patent.

Patented Feb. 24, 1914.

Application filed November 4, 1913. Serial No. 799,184.

To all whom it may concern:

Be it known that I, NESTOR KALLIOINEN, a citizen of the United States, residing at Negaunee, in the county of Marquette and State of Michigan, have invented new and useful Improvements in Railway-Ties, of which the following is a specification.

The present invention relates to improvements in metallic ties for railway rails, and 10 the object of the invention is the provision of a tie, constructed of steel or other suitable metal which shall comprise a pair of companion members which when associated will interlock.

15 Another object of the invention is the provision in a metallic tie of a pair of interlocking sections, making up the tie, each of which being so constructed and having its parts so arranged that when assembled the same will be prevented from accidental 20 separation, and further wherein the said tie is integrally formed with means for supporting the rails thereon.

With the above recited objects in view, 25 and others which will appear as the nature of the invention is more fully understood, the improvement resides in the construction, combination and operative arrangement of parts set forth in the following specification 30 and falling within the scope of the appended claims.

In the drawings there has been illustrated 35 a simple and preferred embodiment of the improvement reduced to practice, but the nature of the invention necessarily renders the same susceptible to such minor changes as fall within the scope of the appended claims.

40 In the drawings: Figure 1 is a perspective view of a rail tie constructed in accordance with the present invention, Fig. 2 is a transverse sectional view approximately on the line 2—2 of Fig. 1, and looking in the direction of the arrow, Fig. 3 is a similar sectional view on the line 3—3 of Fig. 1, Fig. 4 is a sectional view on the line 4—4 of Fig. 2, Fig. 5 is an enlarged detail central longitudinal sectional view through one end of the tie, Fig. 6 is a bottom plan view of 45 the tie, Fig. 7 is a perspective view of one of the members of the tie, and Fig. 8 is a similar view of the companion section or member of the tie.

50 My improved tie comprises two companion sections formed of some suitable material, such as steel or the like, and each of

the said members is adapted to be stamped from the same die. Each of the sections includes a substantially rectangular member 1 and 2 respectively. Each of the members 1 and 2 is provided with an end flange 3 and with a side flange 4. Each of said sections has a portion of its upper face elevated, the stepped face being, however, flat and horizontally straight and the riser between the steps forms a transverse shoulder which is designated by the numeral 5. The elevated flat portion of each of the sections is arranged inwardly of the said section, or upon that portion of the section opposite to that 70 formed with the end flange 3, the said elevated portion being designated by the numeral 6, while the reduced or lower stepped portion is designated by the numeral 7. The surface 7 at a suitable point away 75 from its end flange 3 is formed with a V-shaped slot, the metal between the slot being bent upwardly to form a rail engaging flange or lip 8, the said lip pointing inwardly of the section, while the stepped surface 6 is also provided, adjacent its free end, with a similarly V-shaped slot, the metal of which being projected upwardly to provide a rail engaging lip 9. The side flange 4 is of an equal width throughout, so 80 that the portion of the flange formed upon the surface 7 has its edge arranged below the portion of the flange provided upon the surface 6, as clearly illustrated in the drawings, and the end of the elevated portion, 85 step or platform 6 is formed with a rectangular cut-away portion from its side not provided with the flange 4, the longitudinal wall or edge formed by the said cut-away portion providing what I will term a 90 stop 10, the purpose of which will presently be set forth. It should be stated that the lip 9 extends outwardly or toward the end of the section opposite its flanged end 3. The step 7, at its juncture with the shoulder 95 5, is bent downwardly and angularly to provide a wing 11, the said wing terminating upon the edge of the section not provided with the flange 4, forwardly of the lip 8 so that only approximately one-half of the section is thus provided with the shoulder or 100 riser 5, and further that the lower angular edge of the wing 11, directly below the shoulder 5, extends downwardly a suitable 105 distance below the lower edge of the said flange 4. The stepped portion 6 of each of the sections is cut longitudinally from its 110

unflanged side or edge a slight distance away from the step 5, the said cut portion terminating in a transverse wall 12 which provides a pocket between the end or edge 5 of the member 6, the shoulder 5 and the outer edge of the wing 11.

In assembling the sections, the section 1 is first placed upon the roadbed, the section 2 is then moved toward the section 1 so that 10 the elevated portions 6 of one of the sections overlies the portions 7 of the said sections 1 and further wherein the stops 10 contact with the opposite edges of the lips 8. The shoulders 5 are contacted by the inner trans- 15 verse edges of the opposite elevated or stepped portions 6 of the co-acting sections, while the inner edges of the shoulders en- gage within, what I will term, the pockets 12 and brought into engagement with each 20 other. If desired, suitable means, such as nuts and bolts, may pass through the sections for securing the same together, but from practice I have found that the flanges 3 and 4 as well as the angular wings 11, 25 when properly embedded within the road- bed and the same properly tamped beneath the ties, through the openings provided by the ends of the longitudinal flange or side flanges 4 and the end flanges 3, additional 30 securing means for the sections are not ab- solutely necessary.

Having thus described the invention, what I claim is;

1. A tie comprising two companion sec- 35 tions, each including a substantially rectangular member having an end flange and a side flange, the top of each of the ties being stepped to provide an elevated portion and a transverse shoulder arranged between the 40 elevated and the reduced portions, the side edges of the reduced portions of the sections, opposite their flanged sides, being bent downwardly and angularly from their shoul- ders to provide wings which terminate a 45 distance from the flanged ends of the said sections, and the sections, when assembled, having their elevated portions resting upon their reduced portions and their transverse shoulders contacting.

50 2. A rail tie comprising two companion sections each including a substantially rectangular member having a finger and flange and a single side flange, the top of each of the sections being stepped to provide a 55 lower and an elevated straight flat surface and a vertical riser between the said surface, the lower steps of each of the sections being bent downwardly from approximately centrally of the risers toward their un- 60 flanged edges, and the elevated portions of the sections at the risers being slotted, and the sections when assembled having their elevated portions resting upon their reduced portions, their steps contacting, their flanged 65 edges, and the walls provided by the re-

cesses at the risers also contacting, and means for connecting the sections.

3. A stamped tie comprising two com- 70 panion sections, the upper face of each of the sections being stepped, the elevated portion of one of the said upper faces adapted to rest upon the reduced portion of the co-acting section when the ties are assembled, rail engaging means integrally formed with the sections, and means for connecting the 75 sections.

4. A stamped tie comprising two com- 80 panion sections, each comprising a stepped mem- ber, the elevated steps of one of the mem- bers adapted to be arranged upon the lower 80 step of the co-acting member to provide the upper face of the tie flat and straight, and rail engaging means integrally formed with the tie.

5. A stamped rail tie formed with two 85 companion members, each including a sub- stantially rectangular member having a sin- gle side flange and a single end flange, the side flanges and the top faces of the sec- tions having one of their portions elevated 90 above their remaining portion to provide a transverse shoulder, the reduced portions of each of the members being bent downwardly and angularly to its unflanged edge from approximately centrally of the shoulder, the 95 elevated portion of each of the ties at the shoulder and wing being recessed to provide a pocket, the sections adjacent their ends being stamped to form upwardly extending V-shaped rail engaging clips, the sections 100 when assembled adapted to have their ele- vated portions rest upon their reduced por- tions, the shoulders to contact, the walls pro- vided by the pockets to be brought into frictional contact, and the unflanged edge of one 105 of the elevated portions of each of the sec- tions to contact with one of the upturned rail engaging clips.

6. A rail tie comprising two companion 110 sections each formed of a flat substantially rectangular member, each having one side flange and one end flange, a portion of each 115 of the flat faces of the sections being ele- vated and continued in a plane parallel with the plane of the remaining portion, the elevated portions of each of the sections be- 120 ing adapted to rest upon the reduced por- tions thereof, each of the sections having in- tegrally formed rail engaging clips which extend toward their ends not provided with the flanges, the ends of each of the sections opposite the flanged end thereof being cut longitudinally and transversely whereby 125 each of said ends may underlie the rail en- gaging clip of the co-acting section and to have the longitudinal walls provided by the said cut away portion contact with one of the edges of the said outer rail engaging lips.

7. A rail tie made up of stepped sections, 130

one arranged upon the other to provide a horizontally straight face for the tie, the said tie being formed with side and end flanges, the side flanges upon the adjacent 5 sides of the tie at diagonal points terminating a distance away from the end flanges, the central portion of the underface of the tie between the flanges being formed with angularly arranged depending wings which 10 have their lower edges gradually decreasing

toward the opposite sides of the tie, and the enlarged ends of the wings being of a greater width than the flanges of the ties.

In testimony whereof I affix my signature in presence of two witnesses.
